**APPARATUS FOR PLUMBING AND
GAUGING POSTS**

Vernon E. Christensen, P.O. Box 304,
Yoncalla, Oreg. 97499
Filed Dec. 30, 1966, Ser. No. 606,127
9 Claims. (Cl. 33—180)

The present invention relates generally to an apparatus for vertically positioning and horizontally spacing ground supported posts and the like.

An extensible, elongate apparatus for the accurate positioning and plumbing of consecutive posts, said apparatus being temporarily suspended intermediate the upper ends of a pair of posts. Post engaging members of the apparatus are urged by resilient means into contact with a plurality of sides of each post and are associated with visual plumbing indicators. Pivot means are provided to permit uniform positioning of guard posts along a curve of a highway to facilitate attachment thereto of a continuous guard rail.

An important object of this invention is the provision of means for vertically positioning or plumbing a loosely set post and simultaneously gauging the spacing of the post from a preceding post. A particularly advantageous use of the present device, though not restrictively so, is in the setting of a series of posts in an equi-distant manner along a roadway wherein each post must be plumbed and located so as to present one of its vertical surfaces substantially parallel to a guard rail for attachment of the latter.

A further important object is to provide a plumbing device including adjustable pivot means for the setting of guard posts along the extended curve of a roadway. In this situation to facilitate bolted attachment of the guard rail to the posts it is important that the outer surface of the post adjacent the guard rail be transverse of that radius of the curve on which the post is located. To locate said surface in such a manner for subsequent attachment of a guard rail, pivotal means are provided by the present invention permitting angular offsetting of each post in a series, the extent of such offset being determined by the radius of the curve and post spacing therealong.

A further important object resides in the means provided allowing convenient engagement of the plumbing members with the post being set wherein said means are resiliently biased into temporary engagement with the sides of the post being plumbed. In a typical post setting operation along a roadway, use of the present device results in a substantial savings in labor man-hours by reason of simply being in rested engagement upon the posts thus obviating the need for auxiliary tools for attachment purposes.

A still further important object is the provision of indices on the apparatus to facilitate adjustment thereof when setting posts along a curve to allow for the reduced spacing between post centers as compared to a straight course of posts.

These and other objects will become subsequently apparent upon a reading of the following specification and drawings referred to therein in which a plumbing device of the nature contemplated by this invention is disclosed.

With reference to the drawings:

FIGURE 1 is a plan view of the present invention with sections removed and operatively disposed intermediate a pair of upright posts;

FIGURE 2 is a side elevational view of FIGURE 1;

FIGURE 3 is a plan view similar to FIGURE 1 with the invention configured for setting posts along a curve of a highway;

FIGURE 4 is an enlarged, detail view of the right hand end member of the present invention as viewed in FIG-

2

URE 1 shown partially in place in full lines against a post and prior to supported engagement of the left hand end member with its posts; and

FIGURE 5 is an end, elevational view of FIGURE 4 with parts broken away and with arm members swung to the broken line position of FIGURE 4.

With continuing reference to the drawings and particularly FIGURE 1 thereof, an apparatus in accordance with the present invention is indicated generally at 1, operatively suspended intermediate a pair of horizontally spaced posts P being plumbed and having surfaces at P1 and P2. The posts P, when of the type supporting a guard rail, are conventionally pre-bored at 2 during manufacture for reception of guard rail fastening elements. For conveniently supporting the present invention bars 3 are temporarily inserted in a friction fit within the bores 2.

The apparatus 1 comprises a telescopic center section having an extensible tubular member 4 supported at its inner end within a main tubular member 5 which is slotted inwardly from its end at 5A and thereat provided with a clamp 6. The extensible tubular member 4 is in the preferred form of the invention pivotally connected to and carries at its outer end a right hand end member 7 while in a similar manner main tubular member 5 carries a left hand end member 8 with both end members being of hollow construction. The terms right hand and left hand are applied simply for descriptive purposes. The pivotal connections above noted include outwardly extending ears 9 and 10 carried respectively by the tubular member 4 and the main tubular member 5 and corresponding ears 11 and 12 carried by the right and left hand end members 7 and 8. Vertical pivot pins are indicated at 13 and 14 and may be nut and bolt assemblies, as shown.

The following description of the right hand end member and the post engaging means carried thereby is equally applicable to both in view of like components which are identified by like numerals.

The present invention is supported at each of its ends by support means in the form of a U-shaped bracket support 15 secured at its base to the outer end of each end member. The arms of U-shaped bracket 15 extend horizontally and have downwardly directed openings 15A formed therein which, as best shown in FIGURE 2, receive the rod 3. The width of each opening 15A gradually diminishes upwardly to permit precise positioning of the bracket arms on rods 3 regardless of varying diameters depending on the diameter of bore 2. Such positioning of the apparatus by the support means insures the desired spacing of the posts and when setting posts along a straight course the alignment of the sides P2 of the posts. The bracket 15 is reinforced by upper and lower diagonal braces 16 welded thereto and to the hollow end members 7 and 8.

Housed within the right hand end member 7 adapted for sliding, rectilinear movement therewithin is a cylindrical carrier 17 constituting part of the post engaging plumbing means, said carrier having an elongated opening 17A (FIG. 4) therethrough and an end plate 20 affixed to its outer end. Bolt 18 extends transversely of the end member and loosely through openings 17A to constitute a limit stop for axial and rotational movement of the carrier. Interposed between the innermost end of the carrier 17 and the closed end of its supporting end member 7 is an expansion coil spring 19 biasing the carrier in an outward direction. The end plate 20, affixed transversely to the exposed end of the carrier 17 (FIGS. 4 and 5) serves as a base for a pair of vertical, transversely spaced hinges 21 having hinge pins 21A. Each hinge includes hinge elements 22 secured to the plate 20 and a central hinge element 23 similarly secured to the inner ends of a pair of opposed right angular arms 24. Accordingly, the arms 24 are each swingably mounted for hori-

zontal movement about the vertical axis of its respective hinge pin 21A into engagement with post sides P2.

The angular arms 24 terminate in inwardly turned, post-engaging portions at 24A and each is apertured at 25 to thereat receive a bolt 26, the head 26A thereof bearing against the post side of the arm and the lock nut 26B bearing upon the outer side of bracket 15. Aligned with and corresponding in size to the apertures 25 are apertures 27 formed in the base of the U-shaped bracket 15, both pairs of apertures being of a diameter to loosely receive the bolts 26 permitting their axial displacement. Pairs of expansion springs 28 are carried by the bolts 26 and bias the angular arms 24 outwardly away from the bracket 15 about the axis of hinge pins 21A to a post engagement as more fully described later.

The transverse end plate 20 serves additionally to support, also in a pivotal manner, visual indicator means indicated generally at 29 including mutually perpendicular bubble-type leveling glasses 30-31 more commonly referred to as spirit levels, for use in plumbing surfaces P1 and P2 in two different vertical planes. Said indicator means is carried by a pivoted upright support 32 having a post-abutting edge 32A and attached to plate 20 in a manner permitting movement about a horizontal axis by a bolt and nut assembly 34 constituting a pivot pin extending intermediate clevis plates 33. The pivoted support 32 merges upwardly with a first level mounting plate 35 which carries in a crosswise manner a second level mounting plate 36, each of which support, respectively, the leveling glasses 30-31. The glasses may be of the conventional type slightly arched along their length to indicate a plumb condition by a centering of the bubble within the liquid carrying glass. Metal casings at 30A and 31A house the ends of the glasses 30-31 and include flanged portions receiving pairs of fasteners 38 and 39 removably attaching same to their respective mounting plates. Each mounting plate is formed to provide a relieved center portion allowing convenient viewing by a workman of both leveling glasses from any angle. From the above-described arrangement of the visual indicator means it will be apparent that the plumb condition of post surface P1 will be indicated by leveling glass 30 while the condition of the two opposite parallel surfaces P2 of the post will be indicated as follows by leveling glass 31. Upon biased engagement of the arms 24 with the post surfaces P2, the plate 20 will tilt transversely, as permitted by carrier 17, to similarly tilt the support 32.

In a post setting operation along a straight course the telescopic center section of the present apparatus is adjusted and locked to selectively space the axially aligned right and left hand end members and particularly the downwardly opening slots 15A in the arms of bracket 15 to correspond to the specified spacing of the post centers. The posts P will previously have been placed in the usual manner within post holes formed on a diameter of a size permitting some degree of displacement of the post center incident to positioning. Additionally, each post will be provided for positioning purposes, with a bar 3 inserted within the bores 2. In the spacing and plumbing of posts for supporting guard rails accurate spacing is critical by reason of the metal guard rail being previously drilled at specified points thus requiring the bore 2 of each post to correspond therewith for reception of guard rail fastening means. Improper spacing of the post can result in costly delays involving the extraction and re-setting of the post.

Prior to completed placement of the present apparatus intermediate a pair of posts, the cylindrical carrier 17 is in an extended position by the action of spring 19 as typically shown in the full lines in FIGURE 4. The extended position of the carrier 17 automatically causes the arms 24 to be swung to an open, post-receiving position by the restraining action of the linkage comprising bolts 26 and springs 28.

In the following description of a typical post spacing

and plumbing operation utilizing the present invention, the post supporting the left hand end member as viewed in FIGURES 1 and 2 may be assumed to have been previously spaced and plumbed by an identical preceding operation.

The cylindrical carrier 17 slidably mounted in the right hand end member 7 is, prior to placement of the apparatus intermediate a pair of posts as aforesaid, in the extended position by action of springs 19. With particular reference to FIGURE 4, the full line position depicts the bracket support and post engaging means partially in place against the post P while in broken lines the same are shown advanced to the fully engaged position as also shown in FIGURE 1. It will be understood that the left hand bracket support (FIG. 1) has been seated on the rod 3 prior to placement of the right hand end member. As the right hand bracket 15 and post are brought into engagement, internal spring 19 is compressed upon support 32 contacting surface P1 to allow seating of the openings 15A on the rod 3 as shown in broken lines in FIGURE 4. The post spacing and alignment is accordingly completed. Simultaneous with the inward movement of carrier 17 relative to the bracket 15 the axes of hinge pins 21A will be displaced permitting the arms 24 to be biased into contact with post surfaces P2 by springs 28.

With placement of the apparatus completed it will be apparent that the plumb condition of surface P1 of the post supporting the right hand end member will be indicated by the levelling glass 30 while the plumb condition of the adjacent sides P2 of the post will be indicated by glass 31. An out-of-plumb condition of the side surfaces P2 will result in the arms 24 transversely tilting plate 20 and hence the normally horizontal axis of pivot pin 34 to tilt level support 32 and the leveling glass 31. As previously noted, the bolt 18 extends loosely through the elongated opening 17A, the clearance there between permitting the slight rotational movement of the carrier and its end plate 20 incident to the last described plumbing operation.

The bracket arms 15 in supported engagement with the rods 3 insures the desired spacing between the two posts and additionally, in the case of posts being set along a straight course, that the corresponding surfaces of each post in a series of posts being in parallel alignment to one another.

As previously noted in the setting of guard rail supporting posts along the curve of a roadway correct placement is complicated by the additional requirement that the outer surface of each post, i.e., the surface adjacent the guard rail, must be at right angles to that radius of the curve on which the post is located. Accordingly, the side surfaces of each post set along the curve of a roadway will necessarily be out of alignment with the remaining posts spotted along the curve. Said surfaces, as typically shown in FIGURE 3, will be offset a predetermined number of degrees depending on the post spacing and the radius of the curve. The offset, once calculated, will determine the angular displacement of both right and left hand end members 7 and 8 about the upright axes of the pivot pins 13 and 14 from the axis of the apparatus' center section. For this purpose a pointer and indices in degree increments as shown in FIGURE 3 may be provided for the sake of convenience.

Further facilitating the placement of posts along a curve is the provision of spacing indices on the extensible tubular member 4 to permit axially adjusting of the said member relative to the main tubular member 5. The spacing indices allow the operator to telescope or shorten the telescoping members to allow for the reduced distance between guard posts along a curve. The reduction will be determined by the radius of the curve with the indices on tubular member 4 being marked with the commonly used radius for highway curves. Accordingly, the shorter the radius of turn, the lesser the distance between the guard posts.

Although shown and described in conjunction with the spacing and plumbing of posts generally rectangular in section it will be apparent to those skilled in the art that with minor modification of the post engaging means the apparatus is equally practical for use with posts circular in section.

While I have shown a particular form of my invention it is to be understood that many minor modifications will be apparent to those skilled in the art, such modifications being within the spirit and scope of the present invention.

Having thus described my invention, what I claim as new and desire to protect by Letters Patent is:

1. An apparatus for spacing and plumbing consecutive ground supported posts comprising in combination, an elongate center section for placement intermediate a

pair of posts and including a pair of end members, bracket support means for said center section carried by said end members and positionable into supported and fixed relationship adjacent to the upper end of both of said posts, and

post engaging plumbing means comprising in combination an elongated carrier slidably supported at one of its ends by and telescopically extendable from at least one end member, pivoted arm means attached to said carrier and positionable into and out of contact with at least two sides of said post, visual plumbing-indicating means supported by said carrier and positionable by said pivoted arm means to indicate the plumb condition of said two sides of one of said posts.

2. An apparatus as claimed in claim 1 wherein said elongate center section includes a pair of expandable members in telescopic engagement for varying the distance between the bracket support means carried by said center section to thereby permit correctly gauging a desired distance between the pair of posts.

3. An apparatus as claimed in claim 2 wherein said end members are connected to said expandable members by pivot means whereby said end members may be horizontally positioned to permit engagement of the support means carried thereby with a pair of posts located along an arc.

4. An apparatus as claimed in claim 1 wherein said pivoted arm means includes a pair of opposed arm members each pivotally supported by said carrier and means linking said arm members to said bracket support means for horizontally positioning said arm members.

5. An apparatus as claimed in claim 1 wherein said post engaging plumbing means further includes an upright support for abutting contact with one side of said post.

5 6. An apparatus as claimed in claim 5 wherein said one end member is of tubular form having an open end to receive internally both said one end of said carrier and an expansion spring for outwardly biasing said carrier to move said upright support carried thereby into contact with said one side of said post.

10 7. An apparatus as claimed in claim 1 wherein said bracket support means comprises a U-shaped bracket including a pair of outwardly projecting arms adapted for supported engagement with a bar temporarily inserted within and extending transversely of a post.

15 8. An apparatus as claimed in claim 4 wherein said linking means restrains said arm members resulting in their horizontal outward movement to a post-receiving position upon extension of said carrier from said end member and conversely said linking means resiliently biases said arm members inwardly to a post-engaging position upon inward movement of said carrier relative to its end member.

20 9. An apparatus as claimed in claim 1 wherein said carrier is supported by said one end member in a manner permitting limited rotational movement of said carrier, said carrier includes a transverse end plate, said pivoted arm means comprises a pair of opposed arm members pivotally carried by said end plate for horizontal swinging movement into biased engagement with opposite sides of said post to tilt said plate, an upright support also carried by said end plate for pivotal movement into abutment with still another side of said post and said visual means comprises a pair of spirit levels horizontally disposed at right angles to each other upon said upright support whereby one of said levels will respond to the plumb condition of said side of said post while the other of said levels will respond to said opposite sides of the post.
